(57) **CLAIM**

The ornamental design for a device to aid in carrying objects with thin, flexible handles, as shown and described.

DESCRIPTION

FIG. 1 is a perspective view of the device to aid in carrying objects with thin, flexible handles of the present invention.

FIG. 2 is a front view of the device.

FIG. 3 is a rear view of the device.

FIG. 4 is a right side view of the device.

FIG. 5 is a left side view of the device.

FIG. 6 is a top side view of the device; and,

FIG. 7 is a bottom side view of the device.
